UNITED STATES PATENT OFFICE.

JOSEPH W. LUCIER, OF KANKAKEE, ILLINOIS.

PHONOGRAPH-STOP.

1,389,368.

Specification of Letters Patent. Patented Aug. 30, 1921.

Application filed October 8, 1920. Serial No. 415,597.

To all whom it may concern:

Be it known that I, JOSEPH W. LUCIER, a citizen of the United States, residing at Kankakee, in the county of Kankakee and 5 State of Illinois, have invented certain new and useful Improvements in Phonograph-Stops, of which the following is a specification, reference being had therein to the accompanying drawing.

10 This invention relates to sound-reproducing machines, and has particular reference to stop mechanism for automatically arresting rotation of the turn-table and its superposed record at any predetermined point.

15 The present invention is an improvement upon and an advance over the particular device disclosed in my co-pending application filed May 8, 1920, Serial No. 379,854. While the structure of that application has, 20 in practical use, been determined to be efficient and useful; nevertheless, it has been found that the improvements herein described and claimed make for a better and more certain operation of the device, and 25 result in a simplified construction.

Briefly, it may be explained here that the structure of my said application includes a stop mechanism which comprises a pointer-mechanism, a brake-device connected with 30 and settable by the pointer-mechanism, a trip-mechanism connected to and for actuating the brake-device and involving a rotating-disk-member on the tone-arm and engageable by a component of the trip-mechanism.

An object of the present improvement is the provision of means whereby resetting of the stop-mechanism may be effected without (as in the structure of my said companion application) removing the pointer-mechanism from its predetermined position to relock the device when it is desired to replay a certain record.

A further object of the invention is the 45 elimination of the aforementioned rotating-disk-member of my companion case and which disk is mounted on the tone-arm of the phonograph for contact with the tripping means, this elimination thereof obviating the necessity of drilling holes in the tone-arm to fasten the disk thereto.

A still further object of the invention is the provision of means for insuring a more positive stopping of the turn-table and its

superposed record by providing for a greater 55 amount of leverage in operating the stop when the machine is playing records with "hill-and-dale" grooves.

Other objects and advantages will be apparent from the following description. 60

In order that the invention may be more readily comprehended, both as to the manner of its application to a phonograph and as to its construction, I have shown in the accompanying drawings one embodiment 65 thereof.

In these drawings:

Figure 1 is a view in top plan of one embodiment of my invention;

Fig. 2 is a view in front elevation thereof; 70

Fig. 3 is a fragmentary sectional view, in side elevation; and

Fig. 4 is a detailed view, in perspective, of a portion of the apparatus.

Referring to these drawings, the numeral 75 1 designates the casing of a sound-reproducing machine of any appropriate type or construction, which is provided with the usual turn-table 2 for supporting the phonograph-record 3 having grooves 4, and a tone-arm 5 80 carrying a reproducer or sound-box 6.

Encircling the tone-arm 5 is a supporting or bearing structure, marked A, which comprises a pointer-supporting member or ring 7 formed with an upstanding portion or 85 collar 8 which is adapted to be readily secured to the tone-arm 5, as by screws 9. Carried by the supporting-member 7 is a pointer-sustaining extension or arm 10.

Preferably and as shown, the collar 8 of 90 the ring 7 has associated therewith a movable trip-carrying member or ring 15 provided with an outstanding member-supporting element or plate 16. Pivots secured to the plate is one member 18 of a toggle, the 95 other member 19 of which turns on a pivot-washer 20 carried by a pivot-post 21 upstanding from the arm 10. Integral with or rigidly secured to the member 19 of the toggle is a limit-setting member or pointer 100 22 which is settable by the operator at different positions over the record to regulate the mechanism for stopping the turn-table 2 at any predetermined point, and which is provided with a downwardly-projecting portion 22a.

Depending from the pointer 22 is a boss 23 forming a connection between the toggle-

member 19 and the pointer 22. The pointer and toggle-member 19 pivot on a screw 24 threaded into the arm 10.

Depending from the projection 16 and near the inner portion thereof is a bifurcated stud 25 in which is pivotally mounted a supporting or bearing structure, marked A, which comprises a trip-sustaining member 26, movement of which is controlled by a spring 27. Upstanding from the member 26 is an arm engaging trip 28 which extends through an aperture in the plate 16 and which trip is adapted to be engaged by the traveling tone-arm 5. The trip 28 is provided, at its upper portion, with a settable element or extension 29, pivoted at 30, and positionable into the path of movement of the traveling tone arm so as to be engaged thereby when set, and this is adapted for use when playing different makes of records. It has been found in actual practice that records with hill-and-dale grooves therein require a strong braking action to insure positive stopping of the turn-table while records with laterally-cut grooves can be positively arrested with a weaker braking action. To accommodate the stop for machines playing records with either the laterally-cut or hill-and-dale grooves, I have provided the trip 28 with its pivoted extension 29. When playing the laterally-cut record, the extension 29 is adapted to be disposed in a vertical position for contact with the lower portion of the traveling tone-arm. For the purpose of arresting a machine playing a record with hill-and-dale grooves, however, the extension 29 is turned on its pivot 30 and brought into the position shown in full lines in Figs. 2 and 3. In this way the traveling tone-arm is engaged by the extension somewhat sooner than when the extension is in a vertical position and set to stop a laterally-cut record; consequently, this earlier contact with the tone-arm advances the instant of engagement of the brake-member (hereinafter to be described) with the turn-table to effect its earlier operation, which, in practice, has been found desirable when playing records with hill-and-dale grooves.

Normally, the spring 27 has a tendency to move the trip-sustaining member toward the underside of the plate 16, and means (presently to be described) are provided for varying the extent of movement of the member 26. It will be understood, of course, that the position of the trip 28 is such as normally to be in the path of travel of the tone-arm as the same moves across the record in order that it may engage the trip and operate the parts, as will presently be described. The free end of the member is provided with a catch 31.

Pivotedly mounted on the underside of the plate 16 is a brake-member, designated gen-

erally by the reference-character 32, and which is of hammer-like form. This brake-member is provided with an engaging-element or hammer 33 adapted, when the trip is actuated, to contact with and arrest rotation of the turn-table. The hammer is, preferably and as shown, provided with a facing of rubber, felt, or other resilient material 34 which aids in arresting rotation of the turn-table. Disposed at an angle 70 to the hammer and formed as a part thereof is an extension 35 provided with a beveled portion for the purpose of engaging the catch 31 and holding it against movement until the tone-arm is brought into contact 75 with the upstanding trip. A spring 37—secured, as by a screw 38, to the underside of the plate 16—bears against the brake-member and is adapted, when the trip is released, to force the hammer into engagement with the turn-table.

Means are also provided for manually resetting the stop and, as here shown, this comprises a finger-piece 39 secured to the extension 35 and passing through an elongated aperture 40 in the plate 16. This manual resetting-device is particularly adapted for use when the operator desires to replay the record then in position on the turn-table. Ordinarily, to reset the stop 90 for playing the record, the pointer 22 is brought to a position to clear the turn-table so that the record may be removed therefrom. This movement of the pointer throws the plate 16 and the attached brake-mechanism against the edge of the turn-table, causing the hammer to be automatically relocked. Should the operator desire to replay the record, he does not change the position of the pointer over the record, but 95 resets the brake by means of the finger-piece 39.

Means are preferably provided for varying the extent of movement of the brake-member 32; and, as here shown, this comprises a screw 41 threaded through the plate 16, adjacent the trip 28, and adapted to engage the brake. By raising or lowering this screw, the time of release of the hammer can be varied.

Means are also provided for maintaining the movable ring 15 in proper operating position and, as here shown, this comprises a ring-element 42 secured, as by screws 43 threaded therethrough, and engaging the 110 collar 8 of the supporting-ring 7.

For the purpose of maintaining the trip-carrying ring 15 is spaced-apart relation to the base of the ring 7 and to the ring-element 42, suitable washers 44 are inserted therebetween, as shown.

Operation: After the record has been placed on the turn-table, the pointer 22 is brought to the position over the record where it is desired to trip the brake. By 130

moving the pointer in this manner, it will be observed that, through the connected lever arrangement 18 and 19, the plate 16 with the upstanding trip 28 will be moved 5 to the left. If the record to be played is provided with hill-and-dale grooves, the pivoted extension 29 is turned down so that it will engage the traveling tone-arm sooner than when the extension is in an upright 10 position and, consequently, advance the instant of engagement of the brake-mechanism with the turn-table to effect its earlier operation. When the tone-arm has reached 15 that point in its travel where it contacts with the upstanding trip, the pressure thereof causes the trip to yield sufficiently to release the catch 31, permitting the hammer 33 to be forced, by means of the spring 37, against the turn-table and, thus, bring the 20 same and its superposed record to a complete stop.

If it is desired to place another record on the machine, the pointer 22 is turned so that it will permit withdrawal of the record 25 then on the turn-table. In so moving the pointer, the projection 16 is, as above pointed out, carried to the right, forcing the hammer 33 against the turn-table and thus causing it to be automatically relocked by pressing 30 the extension 35 on the hammer and forcing the beveled portion thereon to ride over the catch 31. Thus, it will be seen that the stop is automatically re-set. After the 35 new record has been placed on the turn-table, the pointer is again brought to the proper position on the record for operation. In moving the pointer in this manner, the plate 16 and its attached brake-mechanism are moved out of engagement with the turn-table, which permits the same to revolve, as 40 understood. However, if the operator desires to replay the record then in position on the turn-table, the brake can be manually relocked without moving the pointer (in the 45 manner just set forth) for automatically resetting the brake. This manual resetting, as above pointed out, is accomplished by means of the finger-piece 39 being pushed back by the operator, causing the beveled portion on 50 the extension 35 to be engaged by the catch 31. This obviates the necessity of again locating the pointer over the record at the place where it is desired to stop the operation.

55 From the foregoing description, it will be observed that I have devised an exceedingly simple arrangement whereby positive stopping of a phonograph record is assured, whereby records requiring a stronger brak- 60 ing action to insure positive stopping thereof will also be attained, and whereby manual resetting of the stop mechanism may be accomplished.

While I have shown my invention in the 65 embodiment illustrated, it is to be under-

stood that many changes may be made in the same without departing from the spirit thereof or its scope as set forth in the claims.

What I claim is:

1. Stop mechanism for sound-reproducing devices including a supporting-structure, a pointer shiftable in relation thereto, a brake-mechanism juxtaposed to and settable by the pointer, and means independent of the pointer for setting the brake-mechanism irrespective of the position of the pointer. 70

2. Stop mechanism for sound-reproducing devices including a supporting-structure, 80 a pointer shiftable in relation thereto, a brake-mechanism juxtaposed to and settable by the pointer, and means independent of the pointer for setting the brake-mechanism irrespective of the position of the pointer comprising a manually-movable member connected to the brake-mechanism. 85

3. Stop mechanism for sound-reproducing devices including a supporting-structure, a pointer shiftable in relation thereto, 90 a brake-mechanism juxtaposed to and settable by the pointer, and means independent of the pointer for setting the brake-mechanism irrespective of the position of the pointer comprising a member-supporting element carried by the supporting-structure and provided with a slot, and a manually-movable member working in the slot and connected to the brake-mechanism. 95

4. Stop mechanism for sound-reproducing devices including a turn-table, a bearing-structure associated therewith, a member-supporting element movably carried thereby, a brake-device sustained by the supporting-element and engageable with the turn-table, a manually-actuated member 100 sustained by the element and connected to the brake-device for setting it, a catch-device engageable by the brake-device for holding it in a set position, a pointer movably sustained by the bearing-structure and 105 connected to the supporting-element for shifting it and thereby automatically effecting its engagement with the turn-table to position the brake-device in locking relation to the catch-device. 110

5. Stop mechanism for sound-reproducing devices including a turn-table, a bearing-structure associated therewith, a member-supporting element movably carried thereby, a brake-device sustained by the supporting-element and engageable with the turn-table, a manually-actuated member sustained by the element and connected to the 120 brake-device for setting it, a catch-device engageable by the brake-device for holding it in a set position, a pointer movably sustained by the bearing-structure and connected to the supporting-element for shifting it and thereby automatically effecting 125 its engagement with the turn-table to posi- 130

- tion the brake-device in locking relation to the catch-device, and an arm-engaging trip connected to the catch-device for releasing it from the brake-device.
- 5 6. Stop mechanism for sound-reproducing devices including a supporting-structure, a pointer shiftable in relation thereto, a brake-mechanism juxtaposed to and settable by the pointer, an arm-engaging trip connected to the brake-mechanism for releasing it from its set condition, means independent of the pointer for setting the brake-mechanism irrespective of the position of the pointer comprising a member-supporting element carried by the supporting-structure and provided with a slot, and a manually-movable member working in the slot and connected to the brake-mechanism.
- 10 7. Stop mechanism for sound-reproducing devices including a supporting-structure, a pointer shiftable in relation thereto, a brake-mechanism juxtaposed to and settable by the pointer, an arm-engaging trip connected to the brake-mechanism for releasing it from its set condition, a settable element on the trip and positionable for engaging an associated tone-arm, means independent of the pointer for setting the brake-mechanism irrespective of the position of the pointer comprising a member-supporting element carried by the supporting structure and provided with a slot, and a manually movable member working in the slot and connected to the brake-mechanism.
- 15 8. Stop mechanism for sound-reproducing devices including a turn-table, a bearing-structure associated therewith, a member-supporting element movably carried thereby, a brake-device sustained by the supporting-element and engageable with the turn-table, a manually-actuated member sustained by the element and connected to the brake-device for setting it, a catch-device engageable by the brake-device for holding it in a set position, a pointer movably sustained by the bearing-structure and connected to the supporting-element for shifting it and thereby automatically effecting its engagement with the turn-table to position the
- 20 9. Stop mechanism for sound-reproducing devices including a turn-table, a pointer shiftable in relation thereto, a brake-device juxtaposed to and engageable with the turn-table and automatically settable by the pointer, and a manually-actuated device connected to the brake-device for setting it irrespective of the position of the pointer.
- 25 10. Stop mechanism for sound-reproducing devices including a bearing-structure comprising a pointer-supporting ring-member, a pointer associated with the ring-member, a movable ring-member associated with the first-mentioned ring-member, and a changeable trip-device also associated with the movable ring-member.
- 30 11. Stop mechanism for sound-reproducing devices including a bearing-structure comprising a pointer-supporting ring-member, a pointer associated with the ring-member, a toggle-device connected to the pointer, a movable ring-member associated with the first-mentioned ring-member, and a changeable trip-device also associated with the movable ring-member.
- 35 12. Stop mechanism for sound-reproducing devices including a bearing-structure comprising a pointer-supporting ring-member, a pointer associated with the ring-member, a toggle-device connected to the pointer, a movable ring-member associated with the first-mentioned ring-member and to which the toggle-device is connected, and a changeable trip-device also associated with the movable ring-member.
- 40 13. Stop mechanism for sound-reproducing devices including a bearing-structure comprising a pointer-supporting ring-member, a pointer associated with the ring-member, a toggle-device connected to the pointer, a movable ring-member associated with the first-mentioned ring-member, and to which the toggle-device is connected, a brake-supporting plate carried by the movable ring-member, and a changeable trip-device also associated with the movable ring-member.
- 45 14. Stop mechanism for sound-reproducing devices including a bearing-structure comprising a pointer-supporting ring-member, a pointer associated with the ring-member, a toggle-device connected to the pointer, a movable ring-member associated with the first-mentioned ring-member and to which the toggle-device is connected, a brake-supporting plate carried by the movable ring-member, a spring-pressed brake-member on the plate, and a changeable trip-device also associated with the movable ring-member.
- 50 15. Stop mechanism for sound-reproducing devices including a bearing-structure comprising a pointer-supporting ring-member, a pointer associated with the ring-member, a toggle-device connected to the pointer, a movable ring-member associated with the first-mentioned ring-member and to which the toggle-device is connected, a brake-supporting plate carried by the movable ring-member, a spring-pressed brake-member on the plate, and a changeable trip-device also associated with the movable ring-member and which is provided with a pivoted extension.
- 55 16. Stop mechanism for sound-reproducing devices including a bearing-structure

comprising a pointer-supporting ring-member, a pointer associated with the ring-member, a toggle-device connected to the pointer, a movable ring-member to which the toggle-device is connected, a brake-supporting plate carried by one of the ring-members, a spring-pressed brake-member on the plate, a trip provided with a pivoted extension upstanding from the trip-sustaining member, and a catch on the trip-sustaining member.

17. Stop mechanism for sound-reproducing devices including a bearing-structure comprising a pointer-supporting ring-member, a pointer associated with the ring-member, a toggle-device connected to the pointer, a movable ring-member to which the toggle-device is connected, a brake-supporting plate carried by one of the ring-members, a spring-pressed brake-member on the plate, a trip provided with a pivoted extension upstanding from the trip-sustaining member, and a manually settable catch on the trip-sustaining member.

25 18. Stop mechanism for sound-reproducing devices including a bearing-structure comprising a pointer-supporting ring-member, a pointer associated with the ring-member, a toggle-device connected to the pointer, a movable ring-member to which the toggle-device is connected, a brake-supporting plate carried by one of the ring-members, a spring-pressed brake-member on the plate, a trip provided with a pivoted extension upstanding from the trip-sustaining member, and a manually settable catch on the trip-sustaining member engageable with the brake-member.

19. Stop mechanism for sound-reproducing devices including a turn-table and a tone-arm, said mechanism comprising a support associated with the tone-arm, brake-mechanism associated with the turn-table and movable on the support, a limit-setting member disposed on the support, a connection between the limit-setting member and the brake-mechanism whereby movement of the limit-setting member positions the brake-mechanism, and a trip-member associated with the brake-mechanism.

20. Stop mechanism for sound-reproducing devices including a turn-table and a tone-arm, said mechanism comprising a support associated with the tone-arm, brake-mechanism associated with the turn-table and movable on the support, a limit-setting member disposed on the support, a connection between the limit-setting member and the brake-mechanism whereby movement of the limit-setting member positions the brake-mechanism, and a trip-member provided with a pivoted extension associated with the brake-mechanism.

21. Stop mechanism for sound-reproducing devices including a turn-table and a tone-

arm, said mechanism comprising a support associated with the tone-arm, brake-mechanism associated with the turn-table and movable on the support, a limit-setting member disposed on the support, a connection between the limit-setting member and the brake-mechanism whereby movement of the limit-setting member positions the brake-mechanism, and a trip-member provided with a pivoted extension associated with the brake-mechanism and positionable in the path of movement of and engageable with the tone-arm.

22. Stop mechanism for sound-reproducing machines having a turn-table, a tone-arm movable over the turn-table, and a bearing-structure associated with the tone-arm and relatively stationary in respect thereto; the stop-mechanism including trigger-mechanism carried by the bearing-structure, and a pivoted trip-device engageable with the tone-arm when said arm reaches a predetermined position in its travel over the turn-table.

23. Stop mechanism for sound-reproducing machines having a turn-table, a tone-arm movable over the turn-table, and a bearing-structure in which the tone-arm is mounted and which is relatively stationary in respect to the tone-arm; the stop mechanism including a trigger-device carried by and relatively stationary with the bearing-structure, and a pivoted trip-device movable by the tone-arm into engagement with the trigger mechanism for actuating the same.

24. Stop mechanism for sound-reproducing devices which include a turn-table, a tone-arm, and a bearing-structure for the tone-arm; the stop mechanism including a trigger-device associated with the bearing-structure and relatively stationary thereon with respect to movement of the tone-arm over the turn-table, and a pivoted trip-device associated with the tone-arm and positionable at the will of the operator to provide a variable engagement between it and the trigger-device for actuating the latter.

25. Stop mechanism for sound-reproducing devices which include a turn-table, a tone-arm, and a bearing-structure for the tone-arm; the stop mechanism including a trigger-device associated with the bearing-structure and relatively stationary thereon with respect to movement of the tone-arm over the turn-table, a pivoted trip-device associated with the tone-arm and positionable at the will of the operator to provide a variable engagement between it and the trigger-device for actuating the latter, and a brake-mechanism associated with the trigger-device and operable upon the turn-table when the trigger-device is rendered active by the trip-device.

26. Stop mechanism for sound-reproducing devices which include a turn-table, a

tone-arm movable over the same, and a bearing-structure associated with the tone-arm and relatively stationary in respect thereto; the stop-mechanism including a trigger-mechanism, a brake-device associated with the trigger-mechanism and rendered active thereby to engage the turn-table, and a pivoted trip-device adapted to be engaged by the tone-arm to operate the trigger-mecha-

nism and thereby set the brake-device into 10 motion for engagement with the turn-table.

In testimony whereof I affix my signature in presence of two witnesses.

JOSEPH W. LUCIER.
